US0D1070826S

(12) **United States Design Patent** (10) **Patent No.:** **US D1,070,826 S**
(45) **Date of Patent:** **** Apr. 15, 2025**

(54) **WIRELESS MICROPHONE AND RECEIVER**

(71) Applicant: **George Young**, Shenzhen (CN)

(72) Inventor: **George Young**, Shenzhen (CN)

(**) Term: **15 Years**

(21) Appl. No.: **29/906,547**

(22) Filed: **Nov. 7, 2023**

(51) **LOC (15) Cl.** **14-01**

(52) **U.S. Cl.**

USPC **D14/225**

(57) **CLAIM**

The ornamental design for wireless microphone and receiver, as shown and described.

DESCRIPTION

FIG. 1 is a perspective view of wireless microphone and receiver, showing the new design;

FIG. 2 is a first perspective view of the receiver of a wireless microphone and receiver thereof, the receiver is shown separately for ease of illustration;

FIG. 3 is a second perspective view thereof;

FIG. 4 is a front view thereof;

FIG. 5 is a back view thereof;

FIG. 6 is a left side elevational thereof;

FIG. 7 is a right side elevational view thereof;

FIG. 8 is a top plan view thereof;

FIG. 9 is a bottom plan view thereof;

FIG. 10 is a perspective view of a wireless microphone, of a wireless microphone and receiver, shown separately for ease of illustration;

FIG. 11 is a second perspective view thereof;

FIG. 12 is a front elevational view thereof;

FIG. 13 is a back elevational view thereof;

FIG. 14 is a left side elevational view thereof;

FIG. 15 is a right side elevational view thereof;

FIG. 16 is a top view thereof;

FIG. 17 is a bottom plan view thereof; and,

FIG. 18 is a disassembled view thereof.

The broken lines shown in the drawings depict portions of the wireless microphone and receiver that form no part of the claimed design.

1 Claim, 18 Drawing Sheets
